UNITED STATES PATENT OFFICE.

BENJAMIN F. WINTERHOFF, OF ELKHART, INDIANA.

SHEET-METAL-TUBE-PLANISHING MACHINE.

1,162,536.

Specification of Letters Patent.

Patented Nov. 30, 1915.

Application filed June 18, 1914. Serial No. 845,881.

To all whom it may concern:

Be it known that I, BENJAMIN F. WINTERHOFF, a citizen of the United States, and a resident of the city of Elkhart, in the county of Elkhart and State of Indiana, have invented a new and Improved Sheet-Metal-Tube-Planishing Machine, of which the following is a full, clear, and exact description.

10 Among the principal objects which the present invention has in view, are: to provide a machine for rolling or leveling seams in sheet metal and more particularly for the rolling or leveling of the seams formed in tubes, from which musical instruments are constructed; to provide means for manually controlling the pressure applied in the operation; and to provide rollers and beds of varied shape for peening or leveling the 20 joints formed by welding.

Drawings.—Figure 1 is a side elevation of a planishing machine constructed and arranged in accordance with the present invention; Fig. 2 is a vertical cross-section on an enlarged scale, the section being taken as on the line 2—2 in Fig. 1; Fig. 3 is a detail view on an enlarged scale, showing a fragment of the anvil bed and supporting frame, with a die roll and means for manipulating 30 the same, the section being taken as on the line 3—3 in Fig. 2; Fig. 4 is a detail view in cross-section, the section being taken as on line 4—4 in Fig. 2; Fig. 5 is a cross-section, taken on the line 5—5 in Fig. 2; and Figs. 35 6 and 7 are detail views showing different forms of die wheels, used by the planishing machine herein disclosed.

Description.—As indicated in the above statement, the machine is particularly designed to peen or hammer the seams formed in the manufacture of tubular musical instruments. The seams are universally formed by a preliminary step, where the edges are overlapped and welded. Heretofore the welded joint has been peened in the conventional manner, the operator using a hammer, suitable for the purpose, by which he has carefully beaten the seam to the same thickness as the remainder of the tube. As 40 seen in the drawings, this operation is accomplished by the use primarily of a die roll 12. The roll is provided with suitable trunnions 13. The trunnions 13 are disposed in bearings formed in sliding blocks 14. The 45 blocks 14 are laterally grooved to fit the guide rails 15, with which the heads of the

standards 16 are provided. The standards 16 are rigidly secured to the bed rails 17. The bed rails 17 are in turn supportingly mounted on legs 18, which tie the said rails 60 transversely and thus prevent the spread of the lower ends of the standards 16. A similar office is performed by the tie plate 19.

The roll 12 is elevated and depressed manually by revolving the hand wheel 20. 65 The wheel 20 is rigidly mounted on a shaft 21 vertically disposed in bearings formed in a head block 22. The head block 22 is provided to receive the end thrust of feed screws 23, the upper ends of said screws being provided with wearing nibs 24, which are seated in sockets formed in the under face of said head block.

Intermediate the shanks of the screws 23 and the nibs 24, are transmission gear wheels 75 25, said gear wheels being preferably integral with the said screws. The wheels 25 are centrally provided with hubs, the surfaces whereof rest between the block 22 and the plate 19, as best shown in Fig. 2 of the 30 drawings. The screws 23 are threaded to produce similar actions in the respective blocks 14, with which they are engaged, as a result of the action of the master gear wheel 26. The gear wheel 26 is keyed to the 85 shaft 21, as seen best in Fig. 2 of the drawings. The block 22 is held in position by the bolts 27.

To receive the impact or pressure of the die roll 12, a filler bar 28 is employed. The 90 bar 28 is disposed within the tube 29, which is under treatment. The tube thus furnished, is placed on an anvil plate 30, held in the bed 31. The bed 31 is supported by the rails 17, the upper edges whereof are 95 grooved to form runways for the slides 32, with which the said bed is provided.

Preliminary to treating the tube 29 in the manner performed by the present machine, the edges of the tube are lapped and 100 are welded. The office of the present machine as above indicated, is to reduce the thickness of the welded portion or seam, and it is with this end in view that the filler bar 28 is placed within the tube and 105 the tube thus furnished is placed between the die roll 12 and the anvil plate 30. After the tube and bar 28, have been thus disposed, the hand wheel 20 is manipulated to lower the die roll 12, to force the seam of the tube 110 29 on the bar 28. The bed 31 is passed under the die roll, the pressure applied by

the die roll, being gradually increased and manually controlled. At the end of the operation, it will be found that the seam has been reduced in thickness to coincide with the thickness of the tube at either side thereof. The action of the bed is then arrested; the wheel 20 reversely rotated to lift the die roll from contact with the tube, and the said tube with its bar 28 is then removed from the said bed.

10 To move the bed 31, it is provided with a central rack rail 33, the teeth of which are engaged with the driving pinion 34, constituting the end of a transmission gear train, for transmitting the power imparted to the pulley 35 and the shaft 36 thereof. The pinion 34 is mounted on the shaft 37 with the gear wheel 38, which gear wheel is operatively engaged by a companion gear wheel 39, both of said gear wheels being protectively covered by a guard shaft 40.

I claim:

1. A machine as characterized, comprising a die roll; a bed; driving mechanism for said bed; a plurality of standards, one mounted on each side of said bed, said standards having formed therein, vertical guides; a plurality of sliding blocks mounted in said guides and embodying bearings for said roll; a plurality of feed screws operatively connected with said

sliding blocks and having integrally formed thereon gear wheels disposed in spaced relation; a master gear wheel operatively connected with both of said gear wheels; and a hand wheel fixedly connected with said master gear wheel. 35

2. A machine as characterized, comprising a die roll; a bed; driving mechanism for said bed; a plurality of standards, one mounted on each side of said bed; said standards having formed therein, vertical guides; a plurality of sliding blocks mounted in said guides and embodying bearings for said roll; a plurality of feed screws 40 operatively connected with said sliding blocks and having integrally formed thereon gear wheels disposed in spaced relation; a master gear wheel operatively connected with both of said gear wheels; a hand wheel 45 fixedly connected with said master gear wheel; and a head block mounted upon said standards, and having thrust bearings for said screws to receive the pressure strain imposed on said roll. 50

In witness whereof I have signed my name to this specification in the presence of two subscribing witnesses.

BENJAMIN F. WINTERHOFF.
